UNITED STATES PATENT OFFICE.

JOHN S. TAXIS AND HENRY B. JAMES, OF TRENTON, NEW JERSEY, ASSIGNEES TO HENRY B. JAMES.

IMPROVEMENT IN MAINSPRING ADJUSTMENTS FOR WATCHES.

Specification forming part of Letters Patent No. 122,414, dated January 2, 1872; antedated December 21, 1871.

SPECIFICATION.

We, JOHN S. TAXIS and HENRY B. JAMES, of Trenton, in the county of Mercer and State of New Jersey, have invented certain Improvements for the Adjustment of Mainsprings in Time-Keepers and other movements, of which the following is a specification:

Description of the Accompanying Drawings.

Figure 1 is a watch-barrel and mainspring, enlarged, illustrating the invention on a going barrel. Fig. 2 illustrates the invention as applicable to a stationary barrel, and to the time and striking movements of a clock.

The first part of our invention consists in connecting the outer end of the mainspring, by means of a link, to a stud on the face of its barrel between the center and periphery of the same, for the purpose of reducing the leverage, and consequently the power of the spring upon the barrel during the first two turns in unwinding, before its outer spire comes in friction-tight contact with the rim of the barrel. The second part of our invention consists in the application and arrangement of stops on the link or shifting-arm and on the arbor, for the purpose of preventing the overwinding of the mainspring.

To enable those skilled in the art to make and use our invention, we will proceed to describe its construction and operation.

A in Fig. 1 represents the shifting-arm or link, which is made of tempered steel, by preference, and arranged in a recess formed in the barrel-head or wheel B, so as not to project above the surface of the latter, and to avoid interference with other parts, the recess being sufficiently large to permit of the necessary oscillation of the link. One end of the link is pivoted to a projecting stud, a, which is screwed into the barrel-head in the recess, at a point in about the same vertical plane which the outer spire of the tightly-coiled or wound-up spring occupies in the barrel. Its other end, marked b, being bent down to extend through a slot in the barrel, is attached to the outer end of the mainspring C, hook-

fashion, in the usual manner. The outer end of the mainspring is firmly secured to the arbor D. The spring, attached as above described, acts on the barrel through the link only during, say, the first two turns in uncoiling, by which time its outer spire has braced itself friction-tight against the rim of the barrel, so that it will, during the last turns, act by friction directly on such rim. Thus a differential leverage of the spring is obtained, whereby the power it exerts on the barrel is approximately equalized sufficient for all practical purposes. A stop, e, is on the arbor D, to act against a stop, d, on the lever when drawn to it by the spring in winding. If desirable an extra arm and stop may be arranged on the opposite side of the swivel and screw a, to act in a similar manner in unwinding; or the usual stop-work may be used in combination with the lever adjustment, as described, if preferable. Two levers may be combined to act on opposite sides of the spring, if desired. The lever may act as described if connected with a spring and secured to the wheel or frame, as shown in Fig. 2. e is the spring, f is a socket to secure it and the lever A to the frame E; or the levers and mainsprings C C may be attached and operated in the same manner as in Fig. 1.

I am aware that a patent was granted to Arthur Wadsworth on the 5th day of June, A. D. 1869, in which he describes and claims a mode of attaching the outer end of the spring to a pivoted segment of the rim of its barrel. This invention is distinguished from that just alluded to in the arrangement of the link and the location of its pivotal point, which are such as to effect the approximate equalization of the spring power, in the manner set forth; whereas, no such result is or can be produced by attaching the spring to a link, disposed as said Wadsworth's is, to any greater extent than where the spring is hooked directly to the rim of the barrel.

Claims.

1. Attaching a mainspring to a shifting-arm, A, which is secured at a point within the cir-

cle of the spring, substantially as described, whereby the spring power is reduced and equalized, substantially as specified.

2. The combination of the stop *c*, attached to the winding-arbor of a watch movement, with a stop, *d*, on the shifting-arm *A* attached to the barrel, arranged substantially as de-

scribed, for the purpose of preventing over-winding.

JOHN S. TAXIS.
HENRY B. JAMES.
